UNITED STATES PATENT OFFICE.

HARLOW D. SAVAGE, OF ASHLAND, KENTUCKY, ASSIGNOR, BY MESNE ASSIGNMENTS, TO AMERICAN ARCH COMPANY, OF NEW YORK, N. Y., A CORPORATION OF DELAWARE.

BAFFLE-WALL FOR LOCOMOTIVE FIRE-BOXES.

1,138,045.

Specification of Letters Patent.

Patented May 4, 1915.

Application filed June 9, 1913. Serial No. 772,575.

To all whom it may concern:

Be it known that I, HARLOW D. SAVAGE, a resident of Ashland, in the county of Boyd and State of Kentucky, have invented a new and useful Improvement in Baffle-Walls for Locomotive Fire-Boxes, of which the following is a specification.

This invention relates to baffle walls for locomotive fire boxes.

The object of the invention is to improve the arrangement of fire brick forming such baffle walls, in order to reduce the weight and cost of the fire brick, and particularly to furnish a new and improved form of side brick of simple construction, which are so shaped as to be easily secured in the fire box, which are reversible and can be used on either side of the fire box, and which also can be used in fire boxes where the side walls converge toward each other.

In the accompanying drawing Figure 1 represents a longitudinal section through a fire box provided with my improved baffle wall, the section being taken on the line 1—1, Fig. 2; Fig. 2 is a transverse section on the line 2—2, Fig. 1; Fig. 3 is a plan view of the baffle wall; Fig. 4 is a perspective view of the under side of one of the side bricks.

In the drawings 1 represents the front wall of the locomotive fire box, which is provided with the usual firing opening 2; 3 represents the rear wall of said fire box; 4 the top thereof; and 5 the grate. Extending between the front and rear side walls are the usual longitudinal tubes 6 for supporting the baffle wall. The fire box, as shown, is provided with four such longitudinal tubes 6 which are connected in the circulation system of the boiler, and extend substantially parallel to the central longitudinal axis of the fire box, at least for those portions of the length which support the baffle wall. The side walls 7 of the fire box may be parallel to each other, but in some cases may converge toward the rear wall of the fire box, as indicated in Fig. 3.

The baffle wall is formed, as shown, by five rows of brick, to-wit, three central rows 8, and two side rows 9, which taken together form a sort of inverted arch extending from side to side of the fire box. The brick 10 of the three intermediate rows have their lower end corners cut out, as at 11, to form recessed faces resting upon the four circulation tubes 6, and also have a part of the

brick projecting downwardly between said tubes to prevent lateral movement. The upper end portions of the intermediate brick are preferably sloped back or beveled slightly, as at 12, to prevent the bricks fusing together under the extreme temperatures to which they are subjected. Preferably, also, a slight space is left between the ends of adjacent brick, as at 13, for the same reason, although this is not essential.

The brick 14 of the side rows are inclined between the side walls 7 of the fire box and the outer circulation tubes. They are of special shape, being formed substantially of flat plates of the same thickness throughout, and are curved or arched at their outer edges in two directions, first in a horizontal plane, as indicated at 15, and second in a vertical plane, as indicated at 16. This takes care of any inequalities in the side walls of the fire box, and insures that the side brick will have a firm bearing against the side walls, even if the latter converge toward each other, and also a firm bearing upon the circulation tubes. The under side of each side brick 14 is provided with one or a plurality of downwardly extending lugs or projections 17, two being shown. These lugs or projections are molded integral with the brick and are shaped to form curved bearing surfaces 18, which abut against the outer circulation tubes 6 and prevent the brick from dropping down between said tubes and the walls of the fire box. The lower inner horizontal edges of the bricks 14 are slightly cut away, or beveled, as at 19, to form long bearing surfaces extending the full length of the brick, and resting directly upon the circulation tubes 6. The side brick consequently have in effect a three-point suspension, that is, they bear upon the tubes for substantially their entire length or at both ends and contact with the side walls of the fire box at a single point. This prevents liability of the brick tilting in use or from becoming in any manner displaced from the circulation tubes. The upper inner edges of the brick are also sloped back or beveled slightly, as at 20, to prevent them from fusing with the adjacent intermediate brick under extreme high temperatures. The side brick 14 are also reversible, that is, any brick may be used either on the left or on the right hand side of the fire box, due to their symmetrical

shape and to their curved outer ends. When the side walls of the fire box converge, different side brick longitudinally of the fire box will be of different widths, to take care 5 of the varying distance between the side walls and the outer circulation tubes at different points longitudinally in the fire box. Preferably, the different brick will be of such size that the inclination of all brick 10 will be the same. However, if desired, different bricks can be inclined different amounts.

The brick described are of very simple construction so that they can be readily 15 manufactured, handled and transported. Their shape also makes them materially lighter in weight than other brick for the same purpose. They are all made of such size as to be easily inserted through the 20 firing opening and can be placed upon the circulation tubes in any standard locomotive fire box without requiring alterations therein or the application of any attached means, such as brackets or the like, to the 25 side walls. The inclination of the side brick is such that its weight tends to make it set-

tle more firmly in place and to wedge in between the side walls and the outer circulation tubes.

What I claim is:—

A locomotive fire box comprising in combination, side walls, longitudinally inclined circulation tubes between said side walls, and a brick baffle wall on said tubes comprising intermediate refractory brick resting upon the circulation tubes, and refractory side brick inclined in position and having their outer ends curved in both horizontal and vertical planes and resting against the side walls, the inner edges of said side 40 brick being formed to rest for their full length upon the circulation tubes, and lugs or projections on the lower face of each said side brick and bearing against the circulation tubes.

In testimony whereof, I have hereunto set my hand.

HARLOW D. SAVAGE.
